CAST ALUMINUM REAR LEG AND BACK REST SUPPORT FOR FURNITURE

Robert H. Monroe, East Orange, N. J., and Marvin K. Culbreth, Wilton, Conn., assignors to Molla Incorporated, Westbury, N. Y., a corporation of New York

Application November 21, 1957, Serial No. 48,596

Term of patent 14 years

(Cl. D15—8)

FIG. 1

FIG. 2

FIG. 3

Fig. 1 is an inside view of a cast aluminum rear leg and back rest support for furniture, looking in the direction of the arrow 1 of Fig. 3;

Fig. 2 is a front view of the structure shown in Fig. 1 or, in other words, looking in the direction of the arrow 2 of Fig. 1; and

Fig. 3 is an enlarged sectional view on the line 3—3 of Fig. 1.

We claim:

The ornamental design for a cast aluminum rear leg and back rest support for furniture, as shown.
